WAVE GUIDE OUTPUT WINDOW

Lester Marion Winslow, Stanford, and Herbert John Shaw, Palo Alto, Calif., assignors to Research Corporation, New York, N.Y., a corporation of New York

Application November 29, 1957, Serial No. 699,729

2 Claims. (Cl. 333—98)

The present invention relates to output windows for evacuated ultra-high frequency electron discharge devices and the like and, more particularly, to a vacuum sealing means for high power electron tubes which will efficiently transmit high frequency electromagnetic energy.

Recent developments in the high power tubes for the three centimeter wavelength region have created a need for output windows capable of transmitting peak power in excess of one megawatt and average power in the neighborhood of one kilowatt. Such windows are used in the output waveguides of high-power tubes to allow transmission of RF power from the evacuated output cavities of the tube to a pressurized external circuit.

It has been found that a dielectric element may be employed which can be made transparent to the RF wave by suitable impedance matching. In the prior art such has been accomplished by shaping the dielectric, as, for example, in tapered cone windows and stepped windows, or by utilizing matching sections separate from the dielectric.

The present improved window structure, which may be referred to as a filter window, uses separate matching elements with overall structure suitable for use as a three-element bandpass filter for broad band operation.

The filter window of the present invention comprises resonant elements including resonant metal blocks and a resonant ceramic slab. The ceramic block has a specific loaded Q which is determined by the dielectric constant of the ceramic material, center frequency, and waveguide dimensions. The resonant blocks may be designed to have a specified resonant frequency.

It is an object of the present invention to produce an output window for high power electron tubes capable of efficient broadband transmission.

Another object of the invention is to produce a waveguide window which is vacuum tight and able to withstand large thermal stress and mechanical stress due to the inherent pressure differentials of the pressurized system.

Still another object of the invention is to produce waveguide apparatus for use in a high power electron tube designed to function in the three centimeter wavelength region which is impervious to damage by high energy electron bombardment originating in the output cavity of the tube.

Still a further object of the invention is to produce a device for the transmission of electromagnetic energy which is easy to construct and is compact in size.

These and other objects and advantages are achieved by a construction wherein a ceramic element is employed as the sealing unit at the output end of the device and the remainder of the filter window assembly includes matching metal blocks which establishes the desired electrical impedance characteristics while providing a means for effectively shielding the ceramic element from the deleterious effects of high energy electron bombardment.

The principles of the present invention and other objects and advantages thereof will become more apparent from the following detailed description of the apparatus which will be more completely described with reference to the accompanying drawing, in which:

2

Fig. 1 is a longitudinal section of a preferred embodiment of the invention;

Fig. 2 is a sectional view of the invention taken along lines 2—2 of Fig. 1;

Fig. 3 is a perspective view of the invention shown in Figs. 1 and 2 employed as an output window of a wave guide output klystron tube; and

Fig. 4 is a graphic representation of the transmission properties of the filter window assembly illustrated in Figs. 1 and 2.

Referring to Figs. 1 and 2, there is shown a metallic rectangular waveguide structure, generally indicated by reference numeral 10, having parallel top and bottom walls 12 and 14, respectively, and parallel side walls 16. The section of the waveguide 10 is provided at each end with flanges 18 and 20 having suitable apertures 19 formed therein to accommodate the insertion of fastening means for appropriately securing the waveguide structure to associated apparatus.

The filter window structure illustrated in Figs. 1 and 2 includes an essentially three-section filter having a low insertion loss and an excellent passband. One of the sections is comprised of a ceramic slab or dielectric plug 22 which is opaque to gases and translucent to electromagnetic waves. The material employed for the dielectric plug 22 should be a high strength, vacuum tight, nongassing, low-loss ceramic. It has been found that satisfactory results may be achieved by employing a dielectric material such as WESGO AL-300 which is distributed by the Western Gold and Platinum Works, San Francisco, California. This material contains 97% Al_2O_3 and has the following properties:

WESGO AL 300

Al_2O_3 content 97 percent

Tensile strength	—p.s.i.	26,000—28,000
Compressive strength	—p.s.i.	260,000—285,000
Modulus of elasticity	—p.s.i.	39,000,000
Flexural strength	—p.s.i.	45,000—47,500
Water absorption	percent	0

500	9.90	5.0×10^{-4}	4.9×10^{-3}

The dielectric plug 22 may be metalized at the peripheral portions thereof with moly-manganese and brazed into the waveguide 10. The waveguide wall thickness is reduced as shown at 24 from a thickness of .060 inch to 0.020 inch in the region of the output of the waveguide section where the dielectric plug 22 is to be disposed. The waveguide walls, as at 24, provide for efficient cooling of the interior points, as heat developed within the ceramic material of the plug 22 can be effectively carried away through the conductivity of the materials. The axial distribution of the electric field E within the dielectric is such that E² in the axial center of the dielectric is about 10% of its value in the external waveguide. Thus, from the viewpoint of the gross ratio of heat conductance to the total internal heat developed, a thick dielectric would be more effective than a thin one. Furthermore, a thick ceramic slab results in a rugged assembly which will withstand the forces due to pressurizing of the external waveguide.

The second section of the filter window assembly is comprised of a pair of resonant metal blocks 26 and 28 which are disposed within the waveguide 10 and extend from the bottom wall 14 to the top wall 12.

The remaining section of the assembly is comprised of a resonant block 30 which is centrally located within and extends across the waveguide section 10. The block 30 consists of a metal rectangular parallelepiped placed in the waveguide and with the blocks 26 and 28 functions to periodically change the waveguide impedance.

The metal blocks 26, 28 and 30 are made of copper and may be brazed in the waveguide 10 by the use of Nicor solder while they are adequately held in position by suitably designed jigs.

The arrangement of the second and third sections of the device effectively provides for successful operation at high peak powers by virtue of the optical shielding of the dielectric element 22 which is shielded from any direct optical paths leading from the interior of an associated tube. Such an arrangement avoids breakdown which might otherwise result from electrons reaching the dielectric element 22.

The entire window assembly as above described may be utilized as an output window for a rectangular waveguide output klystron as illustrated in Fig. 3. The invention enables the employment of the rectangular waveguide 10 for coupling energy from the output cavity of a source such as a klystron, indicated generally at 32, to a load. The flange 18 is secured in sealing relationship to the output of the klystron 32 while the ceramic element 22 extends toward the high pressure side of the system. More commonly the flange 18 may be removed and the rectangular waveguide 10 may be brazed directly to the output of the klystron providing a vacuum joint.

By way of illustration, a suitable window assembly for use in connection with a 0.500" x 1.125" rectangular waveguide transmission line system may have the following dimensions:

Wall thickness of the waveguide section	.060".
Ceramic Block 22	.220" x .496" x 1.120".
Copper blocks 26, 28	.124" x .720" x 1.120".
Copper block 30	.250" x .720" x 1.120".
Dimension A	.0742".
Dimension B	.0450".
Dimension C	1.600".

A window assembly having the above dimensions has a resonant frequency of 9000 mc. and a bandwidth of

1430 mc. over which the insertion loss is less than 0.1 decibel. The transmission characteristics of the filter window are illustrated graphically in Fig. 4.

From the above description, it will be appreciated that the objects of the invention have been achieved by the provision of a filter window assembly for providing a pressure seal in a transmission line wherein the ceramic sealing dielectric is effectively shielded from high energy electrons by elements of the assembly which form an integral portion of the assembly. The assembly is of inherent ruggedness to withstand the necessary pressure differentials but provides a minimum of reflection of electromagnetic energy over an extended band of frequencies adjacent to the center frequency and attenuation of frequencies outside the passband. Furthermore, the assembly is capable of functioning at a peak power greatly exceeding that heretofore known in the prior art, and over an extended frequency bandwidth.

We claim:

1. A device for transmitting high frequency electromagnetic energy from an evacuated source to pressurized circuit means comprising a waveguide of rectangular section, a ceramic gas-impervious dielectric member extending transversely across the lumen of the waveguide and sealed to the walls thereof, and a plurality of metallic members extending into the lumen of the waveguide, said metallic members being shaped and positioned to shield said dielectric member from particles traveling in rectilinear paths along said waveguide, whereby said dielectric member and said metallic members present a resonant assembly at the center frequency of the source, to thereby provide low reflection of electromagnetic energy over an extended band of frequencies adjacent to the center frequency and attenuation of frequencies outside the passband.

2. A device for transmitting high frequency electromagnetic energy from an evacuated source to pressurized circuit means comprising a waveguide of rectangular section, a ceramic gas-impervious dielectric member extending transversely across the lumen of the waveguide and sealed to the walls thereof, a first and a second metal block disposed within the evacuated portion of said waveguide, one of said elements mounted on one side of the inner wall of said waveguide and the other of said elements mounted on the other side of the inner wall of said waveguide to thereby define an opening therebetween, and a third metal block disposed within the evacuated portion of said waveguide to optically shield said dielectric member from particles traveling along the longitudinal axis of said waveguide, whereby said dielectric member and said metal blocks presenting a resonant assembly at the center frequency of the source, to thereby provide low reflection of electromagnetic energy over an extended band of frequencies adjacent to the center frequency and attenuation of frequencies outside the passband.
